HYPODERMIC NEEDLE KIT

Albert A. Epstein, New York, N. Y., assignor to
Consolidated Patentees Corporation, New York,
N. Y., a corporation of New York

Application February 4, 1931. Serial No. 513,303

2 Claims. (Cl. 167—3)

This invention relates to a hypodermic needle kit and more particularly to a continuation of the invention disclosed in my copending application filed November 26th, 1930, Serial No. 5 498,322.

The primary object of the invention is the provision of a hypodermic needle kit of simple inexpensive design capable of supporting and protecting hypodermic needle parts when not in 10 use and further to subject the same to a sterilizing action previous to use thereof.

An object of the invention is the combining in a unitary article of a supporting case, a heating device and a sterilizing device.

Another object of my invention resides in the novel manner of designing the lid and box so that they may be interconnected with each other for concealing and protecting the needle parts and capable of separation and support whereby 20 the needle parts may be arranged in a sterilizing solution and heated.

A feature of my invention resides in the use of solid heated elements in combination with a novel design of kit parts whereby a hypodermic needle may be carefully supported and capable of being instantly sterilized under all conditions.

Besides the above my invention is distinguished in the unique manner of designing and manipulating the lid and box so as to provide a support 30 for the box and for the heating element, accomplishing this desired objective at a minimum manufacturing cost.

With these and other objects in view the invention will be better understood from the following detailed description.

Figure 1 is a perspective view of the box in closed position.

Figure 2 is a perspective view of the box in said open position.

40 Figure 3 is a longitudinal sectional view.

Figure 4 is a perspective view of one type of heating element.

Again referring to the drawing illustrating one of the many constructions of my invention, the 45 numeral 1 designates a metallic box for supporting the needle parts 2 in a volume of water or other sterilizing fluid to be heated. Of course, it is to be understood that the needle parts 2 may be carried in a cardboard box for protection 50 within the box 1, when not in use. The same protection can be accomplished by wrapping the needle parts with various materials.

Telescopically connected to the box 1 is a lid 3 designed in a unique manner to enable the same 55 to perform the dual function of a lid for the box

and a support for the box. To accomplish this desired objective and at the same time materially reduce production cost I have designed the lid 3 of a unique construction to be provided with transversely extending projections, supports or 60 beads 4. The surface wall 5 of the lid is depressed preferably at a central point between the beads to provide a fire grate 6 provided with a plurality of perforations 6B to stimulate combustion. To provide cross ventilation, I arrange air inlets 7 65 in the said walls 8 of the lid. The inlets 7 also provide cross ventilation to protect from heat the surface upon which the lid may be supported. Various forms of solid heating or fire elements may be utilized with this particular type of my 70 invention but for the purpose of illustration I have shown these elements 9 in the form of discs 10 which can be formed solely from a combustible material or impregnated with a highly inflammable fluid such as alcohol in which case the 75 discs are hermetically sealed until used.

In my above mentioned copending case I am protecting a paste form of fuel and in this particular application I am protecting a solid form of fuel in the combination, but I wish it to be 80 understood that the grate 6 may be formed without the perforations 6B and a liquid fuel utilized depending upon which is the most advantageous in practice. As there are only three forms of fuel adaptable to my invention, that is to say, a 85 liquid fuel, a paste fuel and a solid fuel, I wish it to be understood that these various types of fuel are to be included in the scope of my invention. Of course, it is to be understood that the lid may be specially designed to function as a gas generator for heating the box but this would involve a 90 considerable increase in production cost.

In the use of my invention the lid 3 when removed from the box 1 is arranged in the position illustrated in Figure 2 to enable the box 1 to be 95 supported directly upon the beads 4.

Supporting the box on the beads 4 separates the bottom of the box from the top surface wall of the lid so that a space will be provided for the heating element during the heating of the sterilizing fluid such as water, in the box. I have shown the fire grate 6 depressed so as to accommodate greater space between the fire element and the bottom of the box but I wish it to be understood that the fire element may be supported in other ways between the spaced surfaces of the lid and the box. When the parts have been set up as just mentioned, a sterilizing fluid such as water is arranged in the box and the needle parts submerged therein. After this has 100 105 110

been accomplished a fuel element 9 is arranged in the fire grate and ignited to heat quickly the water and bring the same to a boiling point for sterilizing the needle parts.

5 Due to the relative size of the box and needle parts it is only necessary to use a relatively small quantity of sterilizing fluid which may be instantly brought to a boiling point through the use of a relatively small amount of heat.

10 Of course, it is to be understood that the various parts may be designed in various ways to carry out the principles of my invention, the main object of the present invention being to accomplish economical manufacture of the article

15 without sacrificing any utility thereof.

Therefore, I do not desire to be limited in protection in any manner whatsoever, except as set forth in the following claims.

What I claim is:

1. A hypodermic needle kit comprising a box, a lid for the box provided with air inlets in the side walls thereof, a centrally depressed fire grate provided with perforations and supporting beads extending transversely of the lid in spaced relation, said box adapted to be supported on said beads. 80

2. As a new article of manufacture, a hypodermic needle kit comprising a lid, supports projecting from the top surface of the lid, a box adapted to be arranged on said supports and a heating element supported by said lid in spaced relation with the bottom surface of said box, said lid provided with air inlets in the side walls thereof and adapted to be telescopically engaged with said box for closing the same. 85 90
